VERTICAL CONVEYER OVEN

Wedworth V. Baker, Detroit, Mich.

Application February 1, 1937, Serial No. 123,549

5 Claims. (Cl. 34—12)

My invention relates to vertical conveyer ovens and an object is to improve the operation of heating, cooling, and oxydizing cores passing through said oven and in this connection the employment of a plenum chamber and horizontal currents.

5 In the accompanying drawings:—

Figure 1 is a diagrammatical vertical central section of an oven embodying my invention.

Figure 2 is a detail section on line 2—2 of Figure 1.

Figure 3 is a detail section on an enlarged scale of that portion of Figure 1, enclosed by the broken line 3—3—3—3, with the carriers at a somewhat lower level.

15 Figure 4 is a detail section on the line 4—4, Figure 2.

Referring now to the reference numerals on the drawings:—

2 indicates the enclosed upper portion of the 20 oven casing. The numeral 4 denotes a dilution chamber shown as concentric with the casing 2, and A4 is a suction chamber. The numeral 5 designates a plenum chamber. Numeral 3 denotes a combustion chamber shown here as located within the dilution chamber 4.

25 Numeral 6 denotes a conveyer apparatus, the carriers 6a, of which, rise at the left of the dilution chamber 4, and descend at the right thereof as indicated by arrows in Figure 1. Numeral 7 30 designates a vent stack and 7a, are openings thereto from the casing 2. Numeral 21 denotes an automatic damper in a passage between the casing 2 and stack 7, which closes by an air, or electric motor, when the temperature reaches an 35 arbitrary limit (say 200°) and again opens automatically when the temperature drops to say 195°. The casing is open to the atmosphere when the apparatus is not in operation.

Numeral 8 denotes openings in the right hand 40 wall of the casing 2, controlled by horizontally operating valves 8a; and 9, are openings in the right hand wall of the suction chamber A4, opposite the openings 8, and correspondingly controlled by the horizontally operating valves 9a.

45 The numeral 10 designates openings through the left hand wall of the plenum chamber 5, and 11 designates corresponding openings through the left hand wall of the casing 2, opposite the openings 10. The openings 10 and 11 are controlled 50 by horizontally operating valves, respectively 10a and 11a. All of the openings 10, except the lowest one open into the plenum chamber 5.

55 Numeral 13 denotes a valve adapted to control the area of passage between the right hand wall of the suction chamber A4, and the opposite wall

of the plenum chamber 5. The valve 13 is located below the upper opening 9. Numeral 14 indicates an opening through the right hand wall of the dilution chamber 4, above the upper end of the plenum chamber 5. Numeral 15 designates 5 a swinging valve adapted to regulate the area of passage through the opening 14.

Numerals 12 indicates a housing covering the openings 11. Numeral 16 indicates a centrifugal fan, its intake passage communicating by a pipe 10 with the interior of the housing 12, and by a branch pipe 18, with the suction chamber A4 at 18a. Numeral 19 denotes stack with which the discharge port of the blower 16 communicates. Numeral 20 denotes a second centrifugal fan, or 15 blower, its intake port communicating through a pipe 21 with the upper end of the dilution chamber as indicated at 21a.

Numerals 22 denotes a pipe connecting the discharge port of the blower 20 with the plenum 20 chamber 5 at 23.

The combustion chamber is a refractory box, usually with steel plate outsides. The gas or oil burner is usually a nozzle type mounted outside the end wall, projecting its flame inside, and 25 through a checkered or slotted top slat into the dilution chamber.

If electricity were the source of heat, the elements would be located where the heater is shown. The heater might even be located outside of the 30 casing and still give the benefits of the design by connecting the circulating system between the pressure and exhaust chambers.

The operation of the above described apparatus is as follows:

35 Hot air having a proper amount of oxygen therein is taken from the upper end of the exhaust chamber 4 and projected into the plenum chamber 5 by the blower 20. The required oxygen is supplied by fresh air taken in through the opening 14, or upper opening 9 or both, the supply being regulated by manipulating the valves 13 and 15. The blower 16 draws the gases from the suction chamber A4 and the housing 12.

The cores passing up at the left are subjected 45 to horizontal currents of gases passing out of the plenum chamber 5 through the openings 10 and being drawn into the opposite openings 11 and discharged through the stack 19.

If a further recirculation of gases is required 50 a pipe may lead from the discharge port of the blower 16 to the upper end of the dilution chamber 4 as shown in Figure 1 in broken lines.

The cores passing downward at the right are cooled by horizontal currents of air entering the 55

casing 2 through openings 8 and into the suction chamber A4 through the opposite openings 9.

Each of the openings through the walls of the casing and chambers may be separately adjusted 5 by its valve, so that the treatment of the cores may be regulated as desired.

Having thus described my invention, what I claim is:

1. In an apparatus of the kind described, a 10 casing, a dilution chamber in said casing, an apparatus adapted to convey carriers in said casing in one direction on one side of said dilution chamber and in the other direction on the other side of said chamber, a plenum chamber, said 15 plenum chamber having an opening to said casing on one side of said dilution chamber and said dilution chamber having an opening to said casing on the other side of said dilution chamber, a heater in said dilution chamber, and means 20 for drawing gas from said dilution chamber and forcing it into said plenum chamber.

2. In an apparatus of the kind described, a 25 casing, a dilution chamber in said casing, an apparatus adapted to convey carriers in said casing in one direction on one side of said dilution chamber and in the other direction on the other side of said chamber, a plenum chamber, said 30 plenum chamber having an opening to said casing on one side of said dilution chamber and said dilution chamber having an opening to said casing on the other side of said dilution chamber, a heater in said dilution chamber, and means 35 for adjusting the area of said openings.

3. In an apparatus of the kind described, a 40 casing, a dilution chamber in said casing, an apparatus adapted to convey carriers in said casing in one direction on one side of said dilution chamber and in the other direction on the other side of said chamber, a plenum chamber, said 45 plenum chamber having an opening to said casing on one side of the dilution chamber and

said dilution chamber having an opening to said casing on the other side of said dilution chamber, a heater in said dilution chamber, and means 5 for drawing gas from said dilution chamber and forcing it into said plenum chamber, and means for severally adjusting the area of said openings.

4. In an apparatus of the kind described, a 10 casing, a dilution chamber in said casing, an apparatus adapted to convey carriers in said casing in one direction on one side of said dilution chamber and in the other direction on the other side of said chamber, a plenum chamber, said 15 plenum chamber having an opening to said casing on one side of said dilution chamber and said dilution chamber having an opening to said 20 casing on the other side of said dilution chamber, a heater in said dilution chamber, and means for drawing gas from said dilution chamber and forcing it into said plenum chamber, said casing having an opening through its wall opposite said 25 opening from said dilution chamber.

5. In an apparatus of the kind described, a 30 casing, a dilution chamber in said casing, an apparatus adapted to convey carriers in said casing in one direction on one side of said dilution chamber and in the other direction on the other side of said chamber, a plenum chamber, said 35 plenum chamber having an opening to said casing on one side of said dilution chamber and said dilution chamber having an opening to said 40 casing on the other side of said dilution chamber, a heater in said dilution chamber, and means for drawing gas from said dilution chamber and forcing it into said plenum chamber, said casing having an opening through its wall opposite said 45 opening from said dilution chamber, and an opening from said casing opposite said opening from said plenum chamber, a housing outside of said casing enclosing the last named opening from said casing, and means for maintaining a 50 vacuum in said housing.

WEDWORTH V. BAKER.
